UNITED STATES PATENT OFFICE.

ELISHA BASSETT, OF LONDON, ENGLAND.

DEVICE FOR EFFECTING THE REGISTRATION OF PLATES FOR MULTICOLOR PRINTING.

Application filed May 12, 1924. Serial No. 712,904.

To all whom it may concern:

Be it known that I, ELISHA BASSETT, a subject of the King of England, residing at London, England, have invented certain

5 Improvements in Devices for Effecting the Registration of Plates for Multicolor Printing, of which the following is a specification.

This invention relates to a device for 10 effecting the registration of plates for multicolor printing, and consists in the provision of two slabs, one of wood for the reception of the lay-out sheet, and one of iron for the reception of the mounting 15 board, the slabs being butted and fixed together and fitted with a hinged frame arranged so that it can be superposed on either slab, a number of double-pointed pins being adjustably arranged in the frame perpendicularly to the plane of the latter so 20 that, after they have been set to certain points on the lay-out sheet, the opposite points can be used on the mounting board for indicating corresponding points on the 25 latter.

Fig. 1 of the accompanying drawings represents a vertical section of the device, and

Fig. 2, an elevation of the same at right angles to Fig. 1 and at a larger scale and 30 showing the frame in upright position.

Fig. 3 is an enlarged section taken on the line 3—3 of Fig. 2.

The device is composed of an iron slab *a* to which marginal rails *b* are secured 35 so as to form a frame. Another slab *c* of wood is butted to the slab *a* and secured to the latter for instance by means of a frame *d* of angle iron which embraces both slabs. An iron frame *e* is hinged to the 40 structure so that it can be superposed on either slab. Preferably the arrangement is such that while the frame *e* lies flat on the slab *e* in one position, as shown by full lines in Fig. 1, it rests on the rails *b* 45 in the other position, as shown by dotted lines. At two opposite sides the frame *e* is formed with internal fillets *f* along which two or more cross-bars *g* can be adjusted, the ends of the cross-bars being forked for 50 engagement with the fillets, as shown in Fig. 3. Clamp-screws *h* are fitted in the forks for securing the bars to the fillets in adjusted position. Each cross-bar has a plurality of threaded studs fitted with nuts 55 *i* by means of which forked or slotted arms *k* can be secured to the bar in any desired

position within the plane of the frame *e*. One end of each arm carries a double-pointed pin *l* which is held perpendicularly to the plane of the frame so that one point 60 can be turned towards the slab *c* and the other towards the slab *a* by a reversal of the frame. The pins may be formed out of a tube one end of which is fitted with a steel point *l'* for use on the slab *c*, the 65 other end being fitted with a non-scratching point *l''*, of ivory, bone, ebony or the like.

When a number of plates are to be printed together, a mounting board *m*, adapted to 70 receive all the plates, is placed on the slab *a* and locked to the frame *b* by means of printer's furniture *n*, as in a chase. A lay-out or guide sheet having impressions of 75 the different plates, is attached to the slab *c* by means of drawing pins, and the frame *e* is superposed thereon as shown by full lines in Fig. 1. Two pins *l* are used for each plate, and these are adjusted to distanced, well defined points on the impression, for instance where lines meet or intersect at an angle, and inserted at such 80 points into the slab *c*. The pins are fixed in adjusted position by means of nuts *i*, whereupon the frame *e* is turned over onto the slab *a*, as shown by dotted lines 85 in Fig. 1. The non-scratching points will then be held over the mounting board *m*, the plates *o* are adjusted on the latter until they register with the pins in the same 90 manner as the corresponding points. When properly adjusted, the plates are nailed to the mounting board which then can be removed for printing. The plates for the 95 other colors are adjusted relative to the pins and fixed to their boards in the same manner.

After the pins *l* have been set relative to the lay-out sheet, it is advisable to check the setting in respect of the opposite pin 100 points in case any of them should be out owing to mechanical defects of the structure. For this purpose a stiff paper sheet is placed loosely on the lay-out sheet, and an impression is taken on it of the pin points. The sheet is then removed and placed either on the points above or, if the sheet should be large, on the mounting board, the frame being superposed on it. Any of these points 105 which do not register properly with the corresponding pin hole, is readjusted accordingly.

As it is necessary for the frame *e* to be quite steady relative to the slabs, it is preferably adapted to turn about center points *p* which are supported in screws fitted in the bearing bracket *q*. In the case of a large apparatus the frame *e* is preferably counterbalanced by weights *r* connected to it by curved arms *s*, as shown by dotted lines in Fig. 2.

10 I claim:—

1. A device for effecting the registration of plates for multi-color printing, comprising an iron slab for the reception of the mounting board, a wooden slab for the reception of the lay-out sheet, the slabs being butted and fixed together, and extending substantially in the same plane, a substantially flat frame, hinge means connecting said frame to said slabs so that it can be superposed on either slab, double-pointed pins arranged adjustably in said frame perpendicularly to the plane of the latter so that they can, by a reversal of the frame, be used for indicating identically related points on the lay-out sheet and on the mounting board and means connecting said pins to said frame.

2. A device for effecting the registration of plates for multi-color printing, comprising an iron slab for the reception of the mounting board, a wooden slab for the reception of the lay-out sheet, the slabs being butted and fixed together, and extending substantially in the same plane, a substantially flat frame, hinge means connecting said frame to said slabs so that it can be superposed on either slab, cross-bars held adjustably in said frame, forked arms connected to said bars so that they can be adjusted longitudinally and angularly thereon in the plane of the frame, and double-pointed pins connected to said arms at right angles to the plane of the frame so that they can, by a reversal of the frame, be used for indicating identically related points on the lay-out sheet and on the mounting board.

3. A device for effecting the registration of plates for multi-color printing, comprising an iron slab for the reception of the mounting board, a wooden slab for the reception of the lay-out sheet, the slabs being

butted and fixed together, and extending substantially in the same plane, a substantially flat frame, hinge means connecting said frame to said slabs so that it can be superposed on either slab, fillets formed at the inside of the frame members, bars held on said fillets across the frame so that they can be adjusted to various positions, and double-pointed pins arranged adjustably on said bars at right angles to the plane of the frame so that they can, by a reversal of the frame, be used for indicating identically related points on the lay-out sheet and on the mounting board.

4. A device for effecting the registration of plates for multi-color printing, comprising an iron slab for the reception of the mounting board, a wooden slab for the reception of the lay-out sheet, the slabs being butted and fixed together, and extending substantially in the same plane, a substantially flat frame, hinge means connecting said frame to said slabs so that it can be superposed on either slab, double-pointed pins arranged adjustably in said frame perpendicularly to the plane of the latter so that they can, by a reversal of the frame, be used for indicating identically related points on the lay-out sheet and on the mounting board, the pins being provided with steel points to face the lay-out sheet and with non-scratching points to face the mounting board and means connecting said pins to said frame.

5. A device for effecting the registration of plates for multi-color printing, comprising an iron slab for the reception of the mounting board, a wooden slab for the reception of the lay-out sheet, the slabs being butted and fixed together, extending substantially in the same plane, a substantially flat frame, hinge means in the form of pointed pivots holding said frame at the junction of the slabs so that it can be superposed on either slab, double-pointed pins arranged adjustably in said frame perpendicularly to the plane of the latter so that they can, by a reversal of the frame, be used for indicating identically related points on the lay-out sheet and on the mounting board and means connecting said pins to said frame.

ELISHA BASSETT.
